UNITED STATES PATENT OFFICE

163,730

COMBINED RADIO, PHONOGRAPH, AND TELEVISION CABINET

Samuel E. Adler, Chicago, Ill., assignor to Admiral
Corporation, Chicago, Ill., a corporation of
Delaware

Application March 22, 1949, Serial No. 1,550

Term of patent 14 years

(Cl. D56—4)

To all whom it may concern:

Be it known that I, Samuel E. Adler, a citizen
of the United States, residing at Chicago, in the
county of Cook, State of Illinois, have invented
a new, original, and ornamental Design for a
Combined Radio, Phonograph, and Television
Cabinet, of which the following is a specification,
reference being had to the accompanying drawing,
forming part thereof.

Fig. 1 is a perspective view of a combined radio,
phonograph, and television cabinet with the doors
open, showing my new design.

Fig. 2 is a similar view thereof with the doors
closed.

The dominant features of my design reside in
that portion shown in full lines in the figures.

I claim:

The ornamental design for a combined radio,
phonograph, and television cabinet, as shown and
described.

SAMUEL E. ADLER.
